(57) **CLAIM**

The ornamental design for a plate, as shown and described.

DESCRIPTION

FIG. 1 is a top perspective view of a plate showing our new design;

FIG. 2 is a top plan view thereof;

FIG. 3 is a side elevation thereof;

FIG. 4 is a bottom plan view thereof;

FIG. 5 is a cross-sectional view of a portion of the claimed design taken along line 5—5 in FIG. 2; and,

FIG. 6 is another view thereof shown on an enlarged scale.
